SAFETY DEVICE FOR RAILWAY CAR DOOR
OPERATING MECHANISM

Albert E. Zimmer, Chicago, Ill., assignor to Enterprise Railway Equipment Company, Chicago, Ill., a corporation of Illinois

Application February 12, 1945, Serial No. 577,463

6 Claims. (Cl. 74—157)

1

My invention relates to improvements in load discharging cars of the type shown in the patent to Argyle Campbell, No. 2,197,237, issued April 16, 1940, and particularly to the door operating mechanism.

One of the objects of the invention is to provide a safety means to prevent the accidental locking of the ratchet mechanism to the winding mechanism shaft during the opening of the doors and the resultant danger of injury to the operator.

Other objects will appear hereinafter.

My invention consists in the provision of means in connection with the pawl and ratchet mechanism for rotating the shaft for preventing the pawl from being accidentally thrown into engagement with the ratchet wheel while the shaft is being rotated at great speed by the doors opening under the weight of the load.

My invention further consists in the combination and arrangement of parts hereinafter described and set forth in the appended claims. The accompanying drawing illustrates one embodiment of the invention.

Fig. 1 is a side elevation of a pawl and ratchet mechanism associated with the door operating mechanism shaft;

Fig. 2 is a vertical transverse sectional view substantially on the line 2—2 of Fig. 1; and

Fig. 3 is an enlarged top or plan view of the mechanism shown in Figs. 1 and 2.

Railway load discharging cars of the type shown in said hereinbefore mentioned patent have dumping doors in their bottom for discharging the load by gravity. These doors are hinged at one side and are supported at their other side by linkage which is wound upon or unwound from an operating shaft when the doors are swung to closed or open position. This linkage is of the self-locking type which locks the doors in closed position by the rotation of the shaft in the direction to wind the linkage upon the shaft. When the shaft rotates in the other direction, the linkage unwinds from the shaft and allows the doors to swing downwardly to open position.

The shaft A is positioned along the side of the car and is extended to the end of the car where it is provided with a ratchet mechanism B which enables the operator to manually rotate the shaft. This mechanism is provided with a socket 1 for the reception of a long removable handle bar C which provides sufficient leverage for the operator. The socket or handle bar member comprises in general two wall members 2 and

3 which are freely rotatable independently of the shaft upon a hub member 4 which is secured or locked to the shaft A, the shaft and the bore of the hub being squared in section for this purpose. The wall members are spaced apart by spacing lugs 5 and 6 and secured in rigid assembly by the rivets 7 and 8 which extend through the spacing lugs.

Between the wall members, the hub 4 is provided with a series of teeth 9 which form a ratchet wheel adapted to be engaged by a pawl member 10, also positioned between the wall members 2 and 3 above the ratchet. The pawl is pivotally mounted on the upper spacing lug 5, being provided with a hub 11 which surrounds the said lug. The pawl is in the form of a short arm having a flat end 12 for engagement with the teeth of the ratchet. These parts are so proportioned that the pawl, when in engagement

20 with the ratchet teeth, is disposed at an angle to a center line through the pivotal axis of the pawl and the center of the shaft A, so that the pawl can be positioned by the operator in engagement with the ratchet teeth on either side 25 of this center line, depending upon which direction the operator desires to rotate the shaft. The pawl is placed in either of these positions by swinging or rotating it in an arc about its pivotal axis, as indicated by the broken line 13 (Fig. 2).

30 If the operator desires to close the doors, he swings the pawl to that side of the center line which corresponds to the rotation of the shaft which winds up the linkage mechanism. If the operator desires to open the doors, he places the pawl on that side of the line in the direction of rotation of the shaft for unwinding the linkage. In this case, he need only rotate the shaft sufficiently to unlock the linkage mechanism, whereupon the weight of the load on the door 35 causes the doors to drop with great force and rapidity and completes the unwinding of the linkage mechanism and rotates the shaft in the same direction at high speed. This disengages the pawl from the ratchet tooth which it happens to be engaging by being struck and swung outwardly by following teeth on the ratchet. It

40 may happen, however, that the pawl is struck with such force that it will be swung about its pivot completely through the arc to the other side of the center line, whereupon it may engage a ratchet tooth and cause the member B and the handle bar C to rotate with the shaft with such suddenness and force as to injure the operator.

45 In accordance with my invention, I provide a

means associated with the ratchet mechanism, which acts to retard or even stop the swing of the pawl about its pivot to the other side of the center line. In the present structure, this retarding means consists of a round protuberance or cam 14 formed at the upper end of the wall member 2 and positioned in the path of the side 15 of the pawl 10 when it is swung in a plane perpendicular to the rivet 7 and surrounding spacing lug 5 on being struck a sharp blow by one of the teeth 9 of the ratchet wheel. It will be understood that the pawl 10 will swing in this manner because of the centrifugal force imparted thereto by such a blow which causes the inner surface portion 16 of the opening through the hub 11 opposite the flat end 12 to engage and slide over the outer surface 17 of the spacing lug 5. Since these surfaces 16 and 17 are disposed at right angles to the wall members 2 and 3, the pawl 10 and particularly the side 15 will swing freely in a plane parallel thereto and the cam 14 will be engaged by one edge or the other of the side 15 depending upon the direction that the pawl 10 is thrown.

In order to permit the pawl 10 to be swung manually past the cam 14 the former is mounted loosely on its pivot provided by the spacing lug 5 with a substantial clearance between the surfaces 16 and 17 as indicated at 18. This clearance 18 permits the pawl 10 to be canted by the attendant relative to the spacing lug 5 sufficiently to move the side 15 clear of the cam 14 and thereby permits the pawl 10 to be swung from one operative position to the other depending upon the direction in which the shaft A is to be rotated.

I claim:

1. In a railway dump car door operating mechanism, a shaft rotatable in either direction for operating said mechanism to open or close the doors, a ratchet mechanism on said shaft including a handle bar for manually rotating said shaft, a pawl for said ratchet mechanism movable manually to either of two positions depending upon the direction in which the shaft is to be rotated, and means to prevent the pawl from being thrown from one position to the other when the shaft is rotated by the opening of the doors under load said means including a fixed cam member fixed relative to the axis of rotation of said pawl and adapted to be engaged by the moving pawl to retard the pawl prior to its reaching said other position.

2. In a railway dump car door operating mechanism, the combination of an operating shaft for said mechanism rotatable in either direction, a ratchet mechanism for manually rotating the shaft in either direction, said ratchet mechanism including an oscillating member rotatable independently of the shaft and having a handle bar for the operator, a toothed ratchet on the shaft, a pawl carried by the oscillating member adapted to engage the teeth of the ratchet in either of two positions depending upon the direction in which the shaft is to be rotated, and a fixed cam member carried by and fixed on said oscillating member and adapted to be engaged by the pawl in its movement from one position to the other to retard the movement of the pawl.

3. In a railway dump car door operating mechanism, the combination of a shaft rotatable in either direction for operating said mechanism, a ratchet mechanism including a handle bar for manually rotating the shaft in either direction, said ratchet mechanism comprising a pair of

spaced members mounted to oscillate on said shaft, a toothed ratchet wheel on the shaft positioned between said spaced members, a pawl pivotally mounted between said spaced members to swing in said space about its pivot in an arc to either of two positions for engagement with the teeth of said ratchet wheel, and a projection on one of said spaced members positioned to reduce the space to a minimum sufficient to allow the pawl to pass the space in its movement from one position to the other.

4. In a railway car door operating mechanism of the type including a shaft, a toothed ratchet wheel secured to said shaft, at least one member abutting said ratchet wheel and mounted for oscillatory movement upon said shaft, and a pivotally movable pawl mounted adjacent said member and carried by said member to swing about its pivot in an arc to either of two positions for engagement with the teeth of said ratchet wheel, retarding means adapted to retard the swing of the pawl about its pivot from one of its two positions to the other, said retarding means comprising a cam integrally formed in said member, and a cam-engaging face on the pawl, the pawl being so positioned that in normal operation the cam-engaging face will engage the cam but will still permit manual movement of the pawl beyond the cam.

5. In a railway car door operating mechanism of the type including a shaft, a toothed operating ratchet wheel secured to said shaft, a pair of spaced members mounted to oscillate on said shaft and abutting said toothed ratchet wheel on either side thereof, and a pawl pivotally mounted between said spaced members to swing in said space about its pivot in an arc to either of two positions for engagement with the tooth of said ratchet wheel, retarding means adapted to retard the swing of the pawl about its pivot from one of its two positions to the other, comprising an immovable projection integral with one of said spaced members and so positioned to reduce the space between said spaced members to a minimum sufficient to allow the pawl to pass the space in its movement from one position to the other, whereby the pawl may be manually moved beyond said projection but will be stopped by said projection in normal operation.

6. In a railway car door operating mechanism wherein a shaft rotatable in either direction to open or close the door is provided having a ratchet wheel secured thereto for rotating the same, in combination, a wall member rockably mounted on said shaft adjacent said ratchet wheel and adapted to be rocked manually thereabout to rotate said shaft, a pawl rotatably mounted on said wall member about an axis parallel to said shaft for movement to either of two operative positions on opposite sides of a line through the axes of said pawl and shaft depending upon the direction in which the latter is to be rotated to place said wall member in driving relation to said shaft, said pawl being likely to be swung to the opposite position by being struck a blow by a tooth of said ratchet wheel on rotation thereof in the same direction that it is being driven by said pawl, and a fixed cam on said wall member in the path of such movement of said pawl adapted to be engaged thereby to prevent its movement to its other operative position, said pawl being loosely mounted on its pivot whereby it can be canted manually with respect thereto

sufficiently far to clear said cam for manual shifting to its other operative position.
